MANIFOLDING ASSEMBLY

Joseph A. Gilbert, Emeryville, Calif., assignor to
 Moore Business Forms, Inc., a corporation of
 Delaware

Application July 21, 1944, Serial No. 545,974

8 Claims. (Cl. 282—8)

This invention relates to improvements in manifolding assemblies, more particularly to such assemblies including a plurality of record and transfer sheets or strips arranged in a unitary assembly for transfer inscription, and particularly adapted for use in writing machines having cylindrical platens adapted to frictionally engage the manifolding assembly to feed it for line spacing and for other purposes.

It is a general object of the invention to provide a manifolding assembly of the class mentioned having an improved structure and arrangement whereby undue bulging or wrinkling or other deformities or irregularities are avoided when the assembly is passed around a cylindrical platen, thus increasing the frictional tractive effort on the assembly when fed over cylindrical platen, particularly platens equipped with friction pressure rolls.

In manifolding assemblies such as the assembly herein disclosed having a flap at one longitudinal edge folded down under along a longitudinal fold line to hold and position record sheets such as loose ledger sheets, considerable difficulty has been heretofore experienced in feeding such manifolding assemblies over cylindrical platens of the friction feed type. This difficulty is caused by bulges, folds and other distortions or irregularities in the manifolding assembly along the longitudinal marginal fold thereof and when the assembly is bent to conform to the cylindrical surface of the platen. Due to such distortions of the assembly there has not been enough frictional tractive effort of the platen surface upon the assembly to effect accurate feeding for line spacing, resulting in slippage causing irregular line spacing, crooked lines, overlapping typing, slowing down of the writing operation, and other unsatisfactory conditions. These difficulties have been effectively overcome by this invention by providing the assembly with an improved structural arrangement for increasing the frictional traction of the cylindrical platen upon the assembly.

Accordingly one of the important objects of this invention is to provide for manifolding assemblies of the class mentioned, an improved structure embodying cutouts or punching along the length of the folded marginal portion of the assembly so as to break up or absorb the bulges and other irregularities and to provide a more uniform frictional tractive surface which is engaged by the frictional feeding surface of the cylindrical platen.

A further object of the invention is to provide

the apertures or cutouts only in the folded flap portion of the assembly which comes into direct engagement with the frictional feeding surface of the platen so as to increase the frictional traction, while the overlying record sheets of the assembly are free from such cutouts or apertures which would result in objectionable mutilation.

Another object of the invention is to provide for easy folding of the record sheet along a longitudinal line by providing scoring or otherwise weakening the paper along the line of traction forming cutouts or apertures, whereby the marginal portion is easily folded under to provide the traction flap.

15 Other objects of the invention will be in part pointed out in the following detailed description of an illustrative but preferred embodiment of the invention, and will be in part obvious as the disclosure proceeds.

20 The invention accordingly comprises the features of construction, combination of elements, and arrangement of parts, which will be exemplified in the construction hereinafter set forth and the scope of the application of which will be indicated in the claims.

25 For a more complete disclosure of the nature, objects and advantages of the invention, reference is had to the following detailed description of the illustrative but preferred embodiment of the invention, and to the accompanying drawing, in which

30 Fig. 1 is a partially diagrammatic perspective view of a part of a manifolding assembly embodying the invention;

35 Fig. 2 is a partially diagrammatic perspective view of a complete manifolding assembly;

40 Fig. 3 is a fragmentary bottom plan view showing the manner of attaching the carbon or transfer sheet;

45 Fig. 4 is a partially diagrammatic enlarged end view of the assembly shown in Fig. 1, parts being broken away and in section; and

Fig. 5 is a partially diagrammatic enlarged end view of the assembly of Fig. 2, parts of the flap being broken away and in section.

50 Referring to the drawing for a detailed description of the illustrative embodiment of the invention there shown, a record sheet 6 of paper or similar material and of any suitable width and length is provided with one or more blank forms 7 for receiving the inscriptions, and has preferably at one of its longitudinal edges a flap 8. This flap as shown preferably extends for the entire length of the record sheet and is separated from the latter by a longitudinal weakened line

9 which may be formed by well known means such as scoring, slitting, perforating or the like. The flap may vary in width somewhat dependent upon the size of the record sheet 6, but will be of sufficient width to provide a support and positioning means for an additional loose record sheet, later described. A flap width of about one and one-half inches has been found to be satisfactory.

A carbon or transfer sheet 10 preferably substantially the same size as the record sheet 6 is attached to the latter so as to form a part of the manifolding assembly. This transfer sheet is provided with an attaching extension 11 extending across the weakened severance line 9 and is attached by a strip or spots of adhesive 12 to the flap 8. The carbon sheet is provided on its lower surface with a coat 13 of transfer material, but the attaching extension 11 is left free from such coating so as to provide a clean attaching margin for the reception of the adhesive.

Preferably extending along a longitudinal marginal portion of the flap 8 and adjacent to the weakened severance line 9 is a row 14 of formations which are preferably in the form of cutouts or apertures 15 which may be either circular as shown or some other shape. While the size of these apertures may vary, a diameter of substantially one-quarter inch has been found in practice to be satisfactory. As later more fully described, these apertures function to avoid undue irregularities in the assembly when passed over a cylindrical platen, so as to break up or absorb the bulges, folds and similar distortions that tend to form when the folded edge of the assembly is bent to conform to the cylindrical platen surface.

As shown in Fig. 2, the flap 8 in its normal operative position is folded to underlie the assembly, being folded substantially along the weakened severance line 9 which thus aids in folding the flap from its flat position shown in Fig. 1 to its normal position in Fig. 2. During such folding operation, the carbon sheet 10 is also folded along the attaching extension 11. When thus folded, the flap 8 provides a support and positioning device for an additional loose record sheet 16 in aligned position with relation to the overlying record sheet 6. It will be seen that the adjacent or overlapping surfaces of the folded flap 8 and of the record sheet 6 are free from attachment with each other thus forming an open receiving pocket in which the loose record sheet 16 is received and supported. This additional record sheet 16 often is made of a width to project at its outer longitudinal edge, slightly beyond the adjacent edge of the sheet 6 and is ordinarily in the form of a loose ledger sheet which may be of slightly heavier stock than the record sheet 6 and of different quality and provided with a blank form similar to the blank form 7. This loose ledger sheet is received at its longitudinal marginal portion within the fold of the flap 8 and is thus properly aligned with the sheet 6. When the ledger sheet 16 is in its normal operative position, its marginal portion wholly overlaps the apertures 15 of the flap 8 as can best be seen in Fig. 5. Also as clearly shown in Figs. 3, 4, and 5, the attaching margin or extension 11 of the carbon sheet 10 is provided with a row of apertures 17 similar to the apertures 15 of the flap 8 and respectively aligned with said apertures 15. It will thus be seen that the apertures 15 and 17 extend only through the flap 8 and the attaching extension 11, and

that the overlying assembly layers including the record sheets 6 and 16 are imperforate or unprovided with apertures corresponding with apertures 15 and 17.

5 As above mentioned, when a record assembly having a longitudinal fold is passed around a cylindrical platen, there is a tendency of the assembly layers to become distorted due to the bending thereof, resulting in bulges, pockets, folds 10 or similar irregularities which tend to decrease the frictional traction of the platen surface upon the assembly. Because of such distortions in the assembly, there is frequently insufficient tractive effort to feed the assembly properly for 15 line spacing and for other purposes, due to the slippage of the platen surface over the surface of the assembly. This improved arrangement of the formations or apertures 15 in the flap 8 which contacts directly with the platen surface, results 20 in a very effective breaking up or absorption of the irregularities and provides a more uniform and regular friction surface so that the frictional feeding effort of the platen is increased and the accurate feeding of the assembly for line spacing, 25 etc., is effected. Also the frictional feeding effort is increased considerably by the presence of the apertures 15 independently of distortion elimination, due to the engagement of aperture edges with the platen surface, and this result is increased when the apertures are overlapped and backed up on the inside by the registering parts 30 of the record sheet 6 or of the ledger sheet 16. Thus it will be seen that irregular line spacing, crooked lines, overlapping typing, etc., will be substantially avoided. Also, the time required for 35 making the manifold inscriptions will be materially decreased.

In some cases it is desirable to provide a selective grip position or formation in the assembly 40 whereby the record sheet 6 can be gripped to the exclusion of the carbon sheet 10. Thus the carbon sheet may be cut out at the corner as indicated at 18. By this means the corner of the record sheet 6 can be gripped to the exclusion 45 of the carbon sheet and severed from the assembly by exerting a tearing pull along the weakened severance line 9, thus severing the record sheet from its binding in the assembly.

50 Since certain changes may be made in the above construction and different embodiments of the invention could be made without departing from the scope thereof, it is intended that all matter contained in the above description or shown in the accompanying drawing shall be interpreted 55 as illustrative and not in a limiting sense.

The invention having thus been fully described, the following is claimed:

1. In a manifolding unit, in combination, a record sheet, a flap positioned along a longitudinal 60 margin of and integral with said record sheet and folded on one side of the latter along a longitudinal fold line into overlapping relation with the record sheet, the adjacent overlapping surfaces of 65 said record sheet and flap being free from each other so as to form a positioning and supporting open pocket for receiving and supporting an additional record sheet, said flap having a longitudinal series of formations extending substantially entirely across the unit adjacent to said fold line 70 so as to prevent bulges, wrinkles or other irregularities in the unit when passed over a cylindrical platen, or the like.

2. In a manifolding unit, in combination, a record sheet, a flap positioned along a longitudinal 75 margin of and integral with said sheet and folded

on one side of the latter along a longitudinal fold line, the adjacent overlapping surfaces of said record sheet and flap being free from each other so as to form a positioning and supporting open pocket for receiving and supporting an additional record sheet, said flap having a longitudinal series of apertures extending substantially entirely across the unit adjacent to said fold line so as to prevent undue bulging or wrinkling or other irregularities in the unit when passed over a cylindrical platen, or the like, and a transfer medium positioned in the unit for transfer inscription and attached to said unit outside of said series of apertures.

3. In a manifolding unit, in combination, a record sheet, a flap positioned along a longitudinal margin of and integral with said record sheet and folded on one side of the latter along a longitudinal fold line so as to form a positioning and supporting means for an additional record sheet, said flap having a longitudinal series of formations substantially coextensive with the length of the unit so as to avoid irregularities when passed over a cylindrical platen, or the like, a longitudinal weakened severance line extending along said series of formations between the latter and said record sheet and providing for severance of the latter, and a transfer medium supported in said unit.

4. In a manifolding unit, in combination, a record sheet, a flap positioned along a longitudinal margin of and integral with said record sheet and folded on one side of the latter along a longitudinal fold line, said flap having a longitudinal series of apertures extending substantially entirely across the unit along and adjacent to said fold line so as to absorb bulges, wrinkles or other irregularities in the unit when passed over a cylindrical platen or the like, and a longitudinal weakened severance line extending along said series of apertures between the latter and said record sheet and providing for severance of said record sheet.

5. In a manifolding assembly, in combination, a record sheet, a flap positioned along a longitudinal margin of and integral with said record sheet and folded on one side of the latter along a longitudinal fold line, said flap having a longitudinal line of apertures extending along and adjacent to said fold line so as to avoid bulging, wrinkles or other irregularities in the assembly when passed over a

cylindrical platen or the like, thus to increase frictional traction with the platen and a transfer sheet in transfer relation with said record sheet and having an attaching margin extending across said tab and having a longitudinal line of apertures similar to said apertures of the tab and respectively aligned therewith.

6. In a manifolding assembly, in combination, a record sheet, a flap positioned along a longitudinal margin of and integral with said sheet and folded on one side of the latter along a longitudinal fold line so as to form a positioning and supporting means for an additional record sheet, said flap having a longitudinal line of apertures adjacent to said fold line so as to prevent undue bulging or wrinkling or other irregularities in the assembly when passed over a cylindrical platen or the like, and a transfer sheet having an attaching margin extending across said fold line and attached to said flap.

7. In a manifolding assembly, in combination, a record sheet, a flap positioned along a longitudinal margin of and integral with said record sheet and folded on one side of the latter along a longitudinal fold line, said flap having a longitudinal line of apertures adjacent to said fold line so as to avoid bulges, wrinkles, or other irregularities in the assembly when passed over a cylindrical platen or the like, and a loose record sheet supported and positioned in the assembly by said flap and having its marginal portion overlapping the said apertures of said folded flap.

8. In a manifolding assembly, in combination, a record sheet, a flap positioned along a longitudinal margin of and integral with said record sheet and folded downwardly on the underside of the latter along a longitudinal fold line, said flap having a longitudinal series of apertures extending substantially across the assembly along and adjacent to said fold line so as to avoid bulges, wrinkles or other irregularities in the assembly when passed over a cylindrical platen or the like, and thus to increase the frictional traction of the platen on said assembly, said record sheet having parts thereof positioned to overlap or register with the respective apertures of said series of apertures of said flap.

JOSEPH A. GILBERT.
